METHOD AND APPARATUS FOR FORMING AND DRIVING AN IMPROVED STAPLE

George H. Reed, Chicago, Ill., assignor to Acme Steel Company, Chicago, Ill., a corporation of Illinois

Application June 19, 1952, Serial No. 294,352

6 Claims. (Cl. 1—82)

This invention relates to an improved method and machine for forming and driving an improved staple and the present machine is a modification of that which is described and claimed in my copending application Serial No. 175,971, filed July 26, 1950, now United States Patent No. 2,635,234, issued April 21, 1953.

The stitching machine and staple forming method of the present invention is an improvement upon the type of machine and method in which flat stitching wire is drawn from a supply coil, fed to the stitching position, and then formed into a staple which is driven through the work to be stitched. In such machines it is desirable to use narrow stapling wire of small gauge which has a tendency to buckle because of its limited column strength and this has made it necessary to guide the staple carefully and to employ great precision in construction. In many machines it is necessary to provide a retractable shoe for supporting the staple in the initial stages of the driving operation to prevent buckling of the staple legs and considerable precision of construction has been required to guide the staple to its driven position. In such a machine the buckling of the staple while being driven has often caused the operation to be arrested by the clogging of the movable parts and any great variation in the gauge of the stitching wire has not been permissible. A further disadvantage of many prior stitching machines has been that lateral curvature in the stitching wire, commonly known as camber, has prevented them from operating successfully.

One object of the present invention is to provide an improved staple formed of a metal strip having some or all of its parts of curved cross section whereby it has great resistance to bending and may be driven by the stitching machine without the use of a supporting shoe and without great precision in the construction of the staple forming and driving parts so that substantial variations in the gauge of the stapling wire are permitted without changing the parts of the machine.

A further object of the invention is to provide an improved method of feeding flat stitching wire to a stitching machine, and to provide an improved method of forming a staple from such stitching wire, wherein the flat wire is moved endwise toward a staple forming position and during its movement is progressively given a concavo-convex transverse curvature whereupon, after reaching the staple forming position, the transversely curved wire is cut and formed into staple-shape. Another object of the invention is to provide, in the foregoing method, the further step of removing from the wire any camber that may be present therein, the camber being removed at the same time the transverse curvature is imparted to the flat wire.

Another object of the invention is to provide an improved stitching machine comprising means for withdrawing flat stapling wire from a supply, imparting a transverse curvature to the wire during its travel, cutting off the wire and giving its ends a predetermined shape, form-

ing the severed section of wire into a staple, and then driving the staple. In this improved machine the legs of the staple may be caused to maintain a parallel or other desired relationship while being driven and the use of a supporting shoe is not required.

Still another object of the invention is to provide a wire stitching machine comprising means for preventing the formation of camber during the feeding of the wire and for removing camber which may be present. A further object is to provide novel means for severing the strip and forming ends of novel form on the legs of the staples. Another object of the invention is to provide an improved staple. Other objects relate to various features of construction and arrangement which will appear more fully hereinafter.

The nature of the invention will be understood from the following specification taken with the accompanying drawings in which one form of apparatus for the practice of the method is shown and one embodiment of the improved staple forming and driving machine is illustrated in connection with several embodiments of the improved staple and certain modifications of parts of the machine which may be employed in producing different forms of staples. In the drawings,

Figure 1 shows a partial front elevation of a staple forming and driving machine embodying the present invention with parts thereof removed and with other parts shown in vertical section;

Fig. 11 shows a sectional view taken on the line 11—11 of Fig. 10;

Fig. 12 shows a sectional view similar to that of Fig. 8, illustrating the relative positions of the parts after the anvil mechanism has been retracted by the downward movement of the staple driver and illustrating the driver after it has partially driven the staple into the work;

Fig. 13 shows a sectional view taken on the line 13—13 of Fig. 12;

Fig. 14 is an enlarged elevation taken on the line 14—14 of Fig. 1, illustrating the cutting mechanism for cutting the stapling wire to form the ends of the legs of the staple with the shape shown in Fig. 2;

Fig. 15 shows an enlarged side elevation of the device illustrated in Fig. 14 with parts thereof broken away,

illustrating the action of the cutting device in severing the stitching wire;

Fig. 16 is a view similar to that of Fig. 14 illustrating a modified form of cutting mechanism adapted to form a straight sharp edge on the stitching wire when it is cut;

Fig. 17 is a view similar to that of Fig. 15 showing the modified form of cutting device illustrated in Fig. 16;

Fig. 18 shows a perspective view of a portion of a staple having a leg which is formed at the end by the cutting mechanism illustrated in Figs. 16 and 17;

Fig. 19 shows an elevation of another form of cutting mechanism adapted to form a staple leg which is sharpened on one side only at its end;

Fig. 20 is a view similar to that of Fig. 14 illustrating the modified cutting device illustrated in Fig. 19;

Fig. 21 shows a perspective view of a portion of the staple having a leg which is sharpened at the end by the form of cutting device illustrated in Figs. 19 and 20;

Fig. 22 shows a partial side elevation and partial section of still another form of cutting device which is adapted to form a blunt end on the stitching wire when it is severed;

Fig. 23 is a view similar to that of Fig. 14 illustrating the modified cutting device illustrated in Fig. 22;

Fig. 24 is a perspective view of a portion of the staple formed by the use of the cutting device illustrated in Figs. 22 and 23;

Fig. 25 shows a modified construction of the staple forming, driving and clinching parts which may be substituted for the corresponding parts in the machine shown in Figs. 1 to 15, inclusive, for producing a circular stitch;

Fig. 26 shows a perspective view of a cylindrical work piece which is encircled by a stitch produced by the modified mechanism illustrated in Fig. 25;

Fig. 27 shows a partial elevation of the driver shown in Figs. 1 to 13, inclusive;

Fig. 28 shows an edge elevation of the driver illustrated in Fig. 27 with the lower edge thereof shown in vertical section;

Fig. 29 shows a vertical section through the work adjacent to a staple which has been formed and driven by the form of mechanism illustrated in Figs. 1 to 13, inclusive, with the type of staple shown in Fig. 2; and

Fig. 30 is a sectional view taken on the line 30—30 of Fig. 29.

As illustrated in the drawings, the apparatus of the invention is embodied in a stitching machine of the type disclosed in United States Letters Patent No. 644,754, granted to Matthew V. Allen on March 6, 1900, and it comprises a stapling head 25 which carries the staple forming and driving mechanism and which is adapted to cooperate with a clincher arm 26 carrying a clincher die 27 adapted to be engaged by the legs of the staple to clinch them on the underside of the parts which are stapled together. The flaps of a fibre-board box, or other parts to be stapled, are placed over the clincher arm 26 and the clincher die 27 occupies a position beneath the point where the staple is to be driven.

The stapling wire 28, drawn from a spool or the like, by means of the feeding mechanism, indicated generally at 30, is fed through a guideway 31 and through a tubular shearing block 32 adjacent which it is cut off to form a length of wire 28a adapted to be formed into a staple above the clincher die 27. While the staple is being formed it is held by the anvil mechanism indicated generally at 34 and, as the staple is driven, this anvil mechanism is retracted to permit the driving of the staple into the work.

The head 25 of the machine comprises a frame or housing 35 having a face plate 36 secured to the front side thereof by screws 37. The face plate 36 is provided on its inner side with a vertical guideway 36a in which a former bar 38 is mounted to reciprocate. The former bar is provided on its outer side with a longitudinal groove 38a of rectangular cross section which is slidably engaged

by a driving bar 40. The former bar 38 has secured to the lower end thereof two staple formers 41 which are held in place by screws 42 and which are provided on their opposed faces with longitudinal grooves 41a adapted to engage the projecting portions of the length of stapling wire 28a to cause the formation of a U-shaped staple in cooperation with parts of the anvil mechanism 34 when the former bar 38 is moved downwardly.

The driving bar 40 has keyed to the lower end thereof a staple driver 43 which is adapted to engage the head of the U-shaped staple and drive it downwardly through the work while at the same time causing the retraction of the anvil mechanism as hereinafter more fully described.

For the purpose of actuating the former bar 38, it is provided between its ends with an aperture engaged by a threaded pin 44 which is held in place by a nut 45 and which is provided with a cylindrical extremity 44a having mounted thereon a roller 46 adapted to travel in a continuous groove 47a formed in a cam 47. This groove has the irregular contour shown in Fig. 1 and the cam has a hub portion 47b which is journaled in a bearing 35a formed in the housing 35. The hub portion 47b is keyed to a shaft 48 which is also journaled in a bearing formed in the housing 35 and which is adapted to be driven at uniform speed by an electric motor or the like. Thus, during the rotation of this shaft the cam 37 is rotated and the former bar 38 is actuated to cause the formation of a staple during each rotation of the cam.

In order to effect the reciprocation of the driving bar 40, this bar is provided at its upper end with a transversely extending pin 40a upon which is journaled a bushing 49 secured in the upper end of a crank arm 50. The lower end of this crank arm is provided with a transversely extending pin 51, shown in Fig. 7A which is journaled in a sleeve 52a formed in the end of a link 52. This sleeve is in turn journaled in a cylindrical recess 47c formed in the face of the cam 47 at a point displaced radially from the axis of this cam. Thus, when the cam 47 is rotated, the pin 51 revolves about the axis of the cam and thereby causes the crank arm 50 to effect a reciprocation of the driving bar 40. The recess 47c in the cam is so located that the downward movement of the driving bar 40 will be effected in proper timed relation to the movement of the former bar 38 so that a staple will be formed and will be in readiness to be driven when the staple driver 43 carried by the driving bar 40 arrives at a position where it is about to engage the formed staple.

The wire feeding mechanism shown particularly in Figs. 1, 3, 4, 5 and 6, is actuated by the previously mentioned link 52 which is actuated by the cam 47. This link is pivotally connected at 54 to a lever 55 which has its lower end pivoted at 56 on a plate 57 mounted for pivotal movement on the casing 35. The reciprocation of the link 52 in response to the rotation of the cam 47 causes an angular oscillation of the lever 55 which actuates a curved link 58 pivotally connected to the upper end of this lever. The other end of this link is pivotally connected at the point 59 to a crank arm 60 which actuates the wire feed mechanism through an overrunning clutch of the type disclosed in United States Letters Patent of Howard G. Allen, No. 1,513,021, dated October 28, 1924, whereby an intermittent feeding movement is imparted to the stitching wire 28.

The crank arm 60 is rotatably mounted upon a shaft 61 located in the housing 62 of the feed mechanism. The crank arm 60 has a pin 63 projecting from the side thereof to engage a slot 64a formed in the side of the clutch driving ring 64 which is mounted to rotate about a clutch disk 65 fixed upon the reduced extremity 61a of the shaft. The disk 65 is provided with side plates 65a which are secured thereto and which overlap at their outer edges the inner margin of the ring 64, as shown in Fig. 3. The disk 65 and its plates 65a are retained against endwise movement of the shaft 61 by a cap member 67 which is secured to the end of the

shaft. The disk 65 is provided with an annular series of spaced pockets 65b in each of which there is mounted a cylindrical roller 66. These pockets are provided with bottom walls 65c which are at right angles to radii of the disk and are so positioned that they converge with the surrounding annular surface 64b of the ring 64 toward one end of the pocket. The roller 66 is thus adapted to wedge between the surface 65c and the surface 64b as it moves toward one end of the pocket but to be released as it moves toward the other end. A coil spring 68 is mounted in each pocket to press the roller 66 normally toward the small end of the pocket and when the ring 64 is rotated in a direction to urge the rollers 66 toward the small ends of the pockets, a driving connection is thereby established between the ring 64 and the disk 65 which is fixed upon the shaft 61. When the crank arm 60 is moved in the reverse direction the ring 64 tends to move the rollers 66 toward the larger ends of the pockets 65b so that the ring 64 then moves around the disk 65 and the shaft 61 remains stationary. In this way, an intermittent rotary motion is imparted to the shaft 61.

This intermittent motion is made use of for effecting an intermittent feed of the stitching wire 28 which passes between two feed wheels 70 and 71. These feed wheels are fixed on the hubs of two gears 72 and 73, respectively, which mesh with each other and cause the feed wheels to be rotated in reverse directions. The gear 72 is secured upon the end of the shaft 61 and the other gear 73 is journaled upon a shaft 74 which is journaled in the frame member 75 in which the shaft 61 is journaled. The feed wheel 70 is provided around its periphery with an annular groove 70a which is engaged by an annular rib 71a formed on the periphery of the feed wheel 71. The stitching wire 28 passes through the groove 70a in the direction of the arrow 76, shown in Fig. 5, and is thereby caused to conform to the curvature of the bottom wall 70b of the groove and to the corresponding curvature of the annular surface 71b of the rib 71a. The curvature of the surface 70b and 71b is such that the metal of the stitching wire is stressed beyond the elastic limit of the metal so that a permanent transverse curvature is thereby imparted to the stitching wire and it has this transversely curved form as it enters the guide 31.

As the stitching wire 28 passes between the feed wheels 70 and 71 it is substantially confined between the surfaces 70b and 71b, with only a slight clearance, and the edges of the metal strip are confined between the side walls 70c of the annular groove 70a. As shown particularly in Fig. 5, the stitching wire is thus confined between the side walls 70c through a substantial distance. Thus, by transversely curving the stitching wire as it is confined between the surfaces 70b and 71b, it is found that any camber which may be in the strip as it comes from the supply reel is substantially reduced. The gears 72 and 73 are fixed on the shafts 61 and 74, respectively, so that they have a limited endwise movement, for example, from .005" to .010", so that as the metal stitching wire advances to the feed wheels from the supply reel, the feed wheels tend automatically to align themselves with the metal strip and thus minimize the possible formation of camber due to unequal distribution of pressure between the contacting portions of the feed wheels as the strip moves between them. In practice, the clearance between the walls of the groove 70a and the annular rib 71a may be on the order of .001" to .002" and it is only necessary that the endwise movement of the feed wheels 70 and 71 be not any greater than the total of the clearances on both sides of the rib 71a.

Since a transverse curvature is imparted to the stitching wire throughout its length as it passes between the feed wheels, it is adapted for use in forming a U-shaped staple, such as the staple 80 shown in Fig. 2, which has a

top wall 80a and parallel legs 80b. All parts of this staple have a curved cross section including the corner portions 80c and the ends of the legs 80b are adapted to be sharpened in the process of cutting off the stitching wire, in the manner hereinafter described, thus producing sharpened extremities 80d which, in this embodiment, are sharpened on both edges so that they are of V-shaped cross section. A staple of this formation has the advantage that the top wall 80a is relatively stiff and is thereafter adapted to resist any bending under the influence of the staple driver. Also, the legs 80b have the advantage that they have substantial column strength so that they resist buckling while being driven, thus making it unnecessary to use the supporting shoe which has heretofore been mounted within the staple to be gradually retracted as the staple is driven. Due to their stiffness and their sharpened extremities, the staple legs may be driven through materials of substantial hardness with which stitching wire has not heretofore been capable of use and, when driving the staple legs through wood, for example, it is not material whether the staple legs extend parallel to or transversely of the grain of the wood.

For the purpose of cutting off the increment of stitching wire 28a which is projected through the anvil mechanism 34, as shown in Fig. 1, the machine is provided with a cutting blade 82 which is attached by a screw 83 to a projecting portion 84a of a bar 84 mounted to reciprocate in a casing 85 on which the stitching wire guide 32 is formed. The casing 85 is attached to the face plate 36 and the bar 84 is mounted for vertical sliding movement therein, being held normally in its upper position by a coil spring 86 which engages a tubular bore formed within the bar, and rests at its lower end on the lower wall of the casing immediately above the stitching wire guide 32.

The cutting blade 82 is provided at its lower end with an arcuate cutting edge 82a which is of V-shaped cross section, as shown in Figs. 14 and 15. When the bar 84 is moved downwardly against the compression of the spring 86, this cutting edge is adapted to cooperate with a stationary cutting die 87 which has an annular V-shaped cutting edge 87a and which is provided with a cylindrical stem 87b mounted in a bore 32b formed in the stitching wire guide. The stationary die 87 is held in fixed position in the guide 32 by means of a setscrew 88 shown particularly in Fig. 14. By releasing the setscrew 88 the stationary cutting die 87 may be rotated to bring a fresh cutting edge to position to cooperate with removable blade 82. The stitching wire 28 advances from the guide 31 to a passage 32a formed in the guide 32 and it emerges immediately above the stationary die 87, as shown in Fig. 1. When the cutting blade 82 is moved downwardly the stitching wire 28 is pressed downwardly against the stationary die 87 and the blade cooperates with the die to cut off the stitching wire 28 and form the arcuate V-shaped cutting edge 80d previously referred to. The curvature of the arcuate cutting edge 82a and the curvature of the corresponding cutting edge 87a on the stationary die should preferably be substantially the same as the transverse curvature of the stitching wire 28, as imparted thereto by the feed wheels 70 and 71, so that the stitching wire is not deformed when it is cut off.

At a proper time in the cycle of operations, the bar 84 is moved downwardly to sever the stitching wire and this is effected by an adjustable pin 90 mounted on an arm 91 which is fixed on a shaft 92 which is journaled in the face plate 36 and arranged to extend into the interior of the housing 35. Within this housing a curved operating arm 93 is secured on the shaft 92 and the tip of this arm is adapted to be engaged by a projection 50a on the lower end of the link 50 so that as the shaft 92 is momentarily rocked in a counterclockwise direction, as viewed in Fig. 1, the bar 84 is caused to be moved downwardly against the compression of the spring 86 and thereby cause the

blade 82 to cut off the length of stitching wire 28a. After the wire is cut off, the former bar 38 is moved downwardly by the cam 47 to form the length of wire 28a into a U-shaped staple 80 having the form shown in Fig. 2, and the driving bar 40 then descends to cause the driver 43 to project the staple downwardly through the work.

For the purpose of adjusting the length of the increment of stitching wire 28a which is fed by the wire feeding mechanism 30 upon each rotation of the cam shaft 48, a handle 95 is provided to turn the plate 57 about its pivot 96 and thus vary the position of the pivot 56 of the lever 55, thereby varying the amplitude of movement of the crank arm 60 upon each reciprocation of the link 52. Also, the plate 57 is provided with an arcuate slot 57a engaged by a roller 97 mounted on a bar 98 attached to the casing 85 and this casing is slidably mounted upon the face plate 36 so that if the plate 57 is adjusted to increase the length of the increment of stitching wire 28a which is fed through the anvil mechanism 34 upon each rotation of the cam shaft 48, the casing 85 will at the same time be adjusted in order to vary the spaced relation of the cutting blade 82 and the shearing die 87 with respect to the anvil mechanism so that both legs of the staple to be formed will be of substantially the same length. These features of adjusting the length of the cut-off sections of staple wire and causing the legs of the staple to be of equal length do not in themselves constitute parts of the present invention.

The anvil mechanism 34 which holds the cut-off section of wire 28a when it is severed by the shearing device, is shown particularly in Figs. 7 to 13, inclusive, and comprises the anvil die 100 which is mounted at the lower end of the anvil carrier 101 pivotally mounted by a pin 102 in a chamber 103a formed in the lower end of a cover block 103 which is secured by screws 104 to the face plate 36. The anvil 100 and the lower part of the carrier 101 are normally caused to swing toward the path of movement of the driving bar 40 by the action of a leaf spring 105 which has its lower end engaging a recess 101a formed in the anvil carrier. The side walls 101b of the recess 101a are bent inwardly to interlock with the curved portion 105a of the spring which is adjacent to its lower extremity 105b. The upper end of the spring 105 extends into a recess 103b formed in the upper inner side of the block 103 where it coats with the bottom edge of the face plate 36, so that it operates normally to swing the lower end of the carrier 101 with its anvil 100 to a position where a V-shaped projection 101c, formed on the anvil carrier, lies in the path of movement of the staple driver 43, as shown, for example, in Fig. 8. At this time the rib 101d, which extends upwardly from the projection 101c, is positioned between the forming dies 41, as shown in Figs. 8 and 9. This spring 105 may be readily removed for replacement by pulling on its upper end.

The anvil 100 has a part 100a over which the cut-off piece of wire 28a is adapted to be bent to form a staple of the form shown in Fig. 2. This part 100a is carried by a small block 100b which is pivotally mounted by a pin 107 between the flanges 101e which constitute the lower extremity of the anvil carrier 101. The part 100b of the anvil die has a tail portion which extends upwardly and rearwardly from the top of the part 100a and this tail portion has an inclined surface 100c which is adapted to engage an inclined surface 101f formed on the anvil carrier 101 between the flanges 101e, thereby limiting the downward movement of the die portion 100a during the formation of the staple. A coil spring 108 is mounted in a recess formed in the rearwardly extending path 100b of the anvil and in the lower part of the anvil carrier and this spring tends normally to move the anvil die 100a to the position shown in Fig. 8 where the pressure of the spring 108 is adapted to cause the anvil to grip the section 28a of the wire between its top face and the lower face of the projection 101c formed on the carrier. The side of the part 101c is provided with a notch or guide-

way 101g of V-shaped cross section which is adapted to engage the end of the wire 28 as it is being fed by the wire feeding mechanism 30 in order to direct the wire into proper position beneath the portion 101c and above the portion 100a of the anvil. The gripping of the wire 28a by the spring actuated anvil 100 continues until the anvil is moved downwardly during the staple forming operation to the position shown in Fig. 10.

After the wire has been positioned in the anvil mechanism in the manner illustrated in Figs. 1, 8 and 9, and after the section 28a of the wire has been cut off by the downward movement of the cutting blade 82, the cam 47 actuates the former bar 38 to cause the former dies 41 to move downwardly and engage the projecting ends of the cut-off piece 28a of the wire. These end portions of this piece of wire pass into the grooves 41a formed in the former dies and, as the former bar 38 moves downwardly, they are bent downwardly to form a U-shaped staple as shown in Figs. 10 and 11. As this downward movement proceeds, the anvil 100 is adapted to tilt about its pivot 107 until the surface 100c engages the surface 101f, as shown in Fig. 10, thus causing the anvil to be firmly supported during the formation of the staple. This movement of the anvil separates the part 100a of the anvil from the projection 101c of the carrier so that the staple is free to move out of engagement with the anvil. This separation of the anvil and the staple is then effected by the downward movement of the staple driver 43 which then takes place in response to the downward movement of the driving bar 40. As the driving member 43 moves downwardly it engages the inclined front face of the part 101c of the anvil carrier and cams this member 101 toward the right, as viewed in Fig. 10, against the action of the leaf spring 105. As the driving member 43 moves downwardly the anvil carrier 101 and the anvil 100 are moved to the position shown in Fig. 12, the staple is disengaged from the anvil 100, and the staple is then driven downwardly by the driver 43 through the work which is supported on the clincher die 27. As the staple is driven, the anvil carrier and the anvil are retained in the retracted position shown in Fig. 12 by the presence of the driving member 43 which then coats with the tip of the projection 101c of the anvil carrier.

After the staple has been driven the driving bar 40 is moved upwardly following the former bar 38 which will have been previously moved upwardly by the action of the cam 47. When the driving member 43 has moved upwardly beyond the projection 101c of the anvil carrier, this carrier is again moved by the spring 105 to the position shown in Fig. 8 and the anvil 100 will be moved by the spring 108 to the position shown in Fig. 8 where it engages a new length of wire fed by the mechanism 30. Thus the cycle of operations may again be repeated with the feeding of a section of wire, the cutting off of that section, the forming of the staple, and the driving of the staple taking place during each rotation of the cam 47. The machine is provided with mechanism, not shown, for insuring that the cam 47 will rotate a single complete revolution during each period when a staple is formed and driven so that all of the parts start and stop their operations in the same relative positions in each cycle.

The staple driving member 43 described above preferably has a lower edge 43b which is arcuate in both right angular directions, as shown in Figs. 27 and 28, so that it conforms to the curvature of the stitching wire 28 and to the top wall 80a of the finished staple in both directions. This prevents any substantial deformation of the staple while it is being driven so that when the staple has been driven and clinched, as shown in Fig. 29, its top wall retains substantially its initial formation and the edges 80e of the staple become embedded in the material 110 which is being secured by the staple. Due to the stiffness imparted to the legs of the staple by the transverse curvature the legs penetrate the material 110 in parallel paths and do not deviate from their intended relation-

ship so that after they have penetrated the material being stapled and have been clinched by engagement with the stapling die 27, the legs are directed toward each other as shown at 80f in Fig. 29, and their extremities are turned upwardly into the material 110 so that they do not catch on surrounding objects. Although no supporting shoe is provided for the staple during the driving operation, it has been found that the use of this supporting device is unnecessary because any tendency of the staple to collapse either by the downward bending of the head of the staple or by the inward buckling of the legs is effectually overcome by the added strength derived from the transverse curvature of the stitching wire which is progressively created in the wire during the feeding operation.

In the embodiment of the invention which has been described above the sharpened ends 80d of the staple are arcuate in cross section, thus facilitating the driving of the staple and the penetration of the material being stapled at the conclusion of the clinching operation. However, there may be instances where other forms of staple legs may be desired and, in Figs. 16 and 17 of the drawings, there is illustrated a modified form of cutting mechanism comprising a cutting blade 112 having a straight cutting edge 112a which is beveled on both sides so that it forms an inclined surface on both ends of the wire which are severed. This blade 112 is adapted to cooperate with a stationary cutting die 113 which is similar to the die 87 except that the cutting head is rectangular in cross section and has four V-shaped cutting edges 113a which are similar in formation to the cutting edge 112a. This cutting die 113 is mounted upon a stem 114 and is adapted to be secured in adjusted position by a setscrew 115. By releasing the setscrew any one of the four cutting edges 113a may be brought into operative position. With the use of cutting devices of the form shown in Figs. 16 and 17, there may be produced a staple 116 of the form shown in Fig. 18 where the leg 116b of the staple has a straight sharp edge 116c of V-shaped cross section.

Another form of cutting mechanism is shown in Figs. 19 and 20 where a cutting blade 120 cooperates with a stationary die 121 secured in operative position by a setscrew 122. The cutting blade 120 has a straight cutting edge 120a of V-shaped cross section and the stationary cutting die 121 is provided with a flat top surface 121a adapted to support the stitching wire on the underside when the cutting blade 120 moves downwardly to sever the wire. The use of the straight cutting edge serves to flatten the stitching wire at the place of cutting and since the cutting occurs only on one side of the wire, the leg 123a of the resulting staple 123, shown in Fig. 21, has a single beveled edge 123c at its extremity. This form of staple leg may be of advantage when it is desired to cause the staple legs to converge upon each other as they are being driven.

Another form of cutting mechanism is shown in Figs. 22 and 23 where the movable cutting blade 125 serves to shear off the stitching wire at the place where it emerges from the passage 32a in the shearing guide 32. The shearing guide thus serves as a stationary die and the resulting staple leg 126b, shown in Fig. 24, has a blunt end 126c which may be desirable when the stapling machine is being used for stapling very light material.

The stitching machine of the present invention may also be employed for forming a circular staple or collar surrounding a cylindrical article or group of articles to be secured or bound. A modified construction capable of producing and driving staples or stitches of this form is shown in Fig. 25 where the former dies 131 have substantially the form previously described but the driver 133 has an arcuate lower end 133a to conform to the semi-circular top wall of the staple 134. The clinching die 135 has a similar semi-circular clinching surface 135a so that when the cylindrical object 136, shown in Fig. 26, is seated on the clinching die 135, the operation

of the driver 133 serves to form the staple into the circular form shown at 134a in Fig. 26 where it surrounds and is partially embedded in the material of the object 136.

From the foregoing description it will be seen that the present invention provides means whereby the flat stitching wire has an arcuate cross section imparted thereto progressively as it is withdrawn from the supply reel and that the camber in the strip is removed as it is arcuately formed so that certain advantages are obtained when staples are formed from the wire and driven into the work. These advantages include the fact that the legs of the staple are straight and have considerable column strength so that they have little tendency to buckle when driven, thus making it unnecessary to provide a staple supporting shoe as in prior machines. Due to the straightness and stiffness of the staple legs, it is possible to use stapling wire of much smaller gauge and width than that required in prior conventional machines and it is possible to drive staples through work pieces having such resistance that they formerly could not be penetrated by staples formed from flat wire and driven by the prior conventional machines. For illustration, the conventional stitching machine can stitch through a maximum of three thicknesses of solid fiberboard, each having a thickness of .100", with the use of flat stitching wire having a thickness of .020" and a width of .103". In contrast with this performance, the stitching machine of the present invention can stitch through six thicknesses of solid fiberboard each having a thickness of .100" when using stitching wire formed into arcuate shape and having a thickness of only .014" and a width of .103". Flat stitching wire having a thickness of only .014" does not give satisfactory results in a conventional stitching machine even when the staple is driven only through a single thickness of fiberboard having a thickness of .100".

Further, it has been found that a conventional stitching machine using flat stitching wire can stitch through three thicknesses of double wall corrugated fiberboard of 600 lbs. tensile test using a stitching wire which is .028" thick and .103" wide but with rather inconsistent results. In contrast with this, staples of arcuate cross section and having straight legs produced by the machine of the present invention may be consistently driven when the stapling wire is only .017" thick and .103" wide. Also, it has been found that conventional stitching machines using flat stitching wire cannot be used to stitch together the layers of cloth and fiber which are employed in the manufacture of buffing wheels where three thicknesses of solid fiber each having a thickness of .080" are secured to twelve thicknesses of cloth having a compressed thickness of about .200". In attempting to stitch the layers of such an article together with the conventional stitching machine using flat stapling wire, it has been found that the resistance is so great that the staple legs buckle instead of penetrating the work but the machine of the present invention using staples formed as described above has been found to work satisfactorily on this type of work with stapling wire having a thickness of .017" and a width of .103".

Another advantage of the present invention is that satisfactory stapling operations may be performed with a lesser compression of the work piece than that required with standard stapling machines employing flat stitching wire. In the operation of the machine described above and in conventional stapling machines, it is common practice for the staple formers to engage the work piece after bending the legs of the staple and to compress the work piece against the staple clincher while the staple is being driven. This has heretofore resulted in some injury to the surface of the work piece by the pressure of the staple formers but, with the present invention, much less pressure of the formers is required while permitting a satisfactory driving of the staple legs of arcuate cross

section and smaller dimensions so that injury to the surface of the work piece is eliminated.

Although several forms of the improved staple of the present invention have been shown and described in connection with the illustration of one form of machine for forming and driving these staples, with modifications of the machine adapted for use with different forms of staples, it will be understood that the staple and the forming and driving machine may be modified in other ways without departing from the scope of the appended claims. The novel features of the stitching machine described above which are not claimed herein are claimed in said copending application Serial No. 175,971, now U. S. Patent No. 2,635,234.

I claim:

1. The method of forming staples one after another from a continuous length of flat stitching wire, comprising the steps of intermittently advancing said wire endwise toward a staple forming position, progressively imparting to said wire during the movement thereof a concavo-convex transverse curvature, severing a predetermined length from the leading end of the transversely curved portion of the wire upon the termination of each advancing movement thereof, and then bending said predetermined length into staple shape.

2. The method of forming staples one after another from a continuous length of flat stitching wire, comprising the steps of intermittently advancing said wire endwise toward a staple forming position, progressively removing camber from the wire and imparting a concavo-convex transverse curvature thereto during the endwise movement of the wire, severing a predetermined length from the leading end of the transversely curved portion of the wire upon the termination of each advancing movement thereof, and then bending said predetermined length into staple shape.

3. The combination in a wire stitching machine, of means for intermittently feeding transversely curved stitching wire in an endwise direction, a die over which said transversely curved wire is fed, a cutting member cooperating with said die to cut said transversely curved wire into lengths, said cutting member and said die having cooperating cutting surfaces conforming in shape to the transverse curvature of said wire for maintaining said curvature in said wire during the cutting thereof, and means for forming said lengths into staples while maintaining transverse curvature therein.

4. The combination in a wire stitching machine, of means for intermittently feeding transversely curved stitching wire in an endwise direction, a die over which said transversely curved wire is fed, a cutting member cooperating with said die to cut said transversely curved wire into lengths, said cutting member and said die hav-

ing cooperating cutting surfaces for maintaining transverse curvature in said wire during the cutting thereof, and means for forming said lengths into staples while maintaining transverse curvature therein.

5. The combination in a wire stitching machine, of means for intermittently feeding transversely curved stitching wire in an endwise direction, a die over which said transversely curved wire is fed, a cutting member cooperating with said die to cut said transversely curved wire into lengths, said cutting member and said die having cooperating arcuate shaped cutting surfaces for maintaining said transverse curvature in said wire during the cutting thereof, and means for forming said lengths into staples while maintaining transverse curvature therein.

6. The combination in a wire stitching machine, of a pair of feed wheels for withdrawing substantially flat stitching wire from a supply and feeding it endwise, one of said wheels having a relatively deep annular groove having radially extending side walls between which the wire passes and the other of said wheels having an annular projection extending into said groove, and means for rotating said wheels, the bottom of said groove and the outer periphery of said projection having cooperating complementary curved surfaces engaging the wire for imparting a transverse curve thereto, said radially extending side walls of said relatively deep groove being spaced apart a distance only slightly greater than the width of the wire for closely confining the lateral edges of the wire both well ahead of and behind the point of contact of said curved surfaces with the wire, whereby lateral curvature is removed from the wire at the same time that a transverse curvature is imparted thereto by said curved surfaces.
